UNITED STATES PATENT OFFICE.

EMIL RITTER v. SKODA, OF PILSEN, AUSTRIA-HUNGARY.

ORDNANCE-SIGHT.

SPECIFICATION forming part of Letters Patent No. 514,969, dated February 20, 1894.

Application filed March 2, 1893. Serial No. 464,304. (No model.) Patented in Belgium October 4, 1892, No. 101,598; in England October 4, 1892, No. 17,672; in Germany October 4, 1892, No. 69,368; in Switzerland October 4, 1892, No. 5,920; in France October 4, 1892, No. 224,716, and in Italy December 31, 1892, XXVII, 32,844, LXIV, 330.

To all whom it may concern:

Be it known that I, EMIL RITTER VON SKODA, manufacturer, a subject of the Emperor of Austria-Hungary, residing at Pilzen, in the Province of Bohemia, in the Empire of Austria-Hungary, have invented certain new and useful Improvements in Sighting Apparatus for Quick-Firing Guns, (for which Letters Patent have been obtained in the following countries, 5 to wit: Belgium, No. 101,598, dated October 4, 1892; Italy, Vol. XXVII, No. 32,844, and Vol. LXIV, No. 330, dated December 31, 1892; England, No. 17,672, dated October 4, 1892; Germany, dated October 4, 1892, No. 69,368; Switzerland, dated October 4, 1892, No. 5,920, and France, dated October 4, 1892, No. 224,716;) and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

25 My invention has relation to gun sights, and more particularly to sights for rapid firing guns, and has for its object the provision of means whereby the range may be quickly obtained and the gun sighted, either by day or 30 by night.

To these ends the invention consists in the combination with a gun, of sights adapted to be rendered visible by night to the gunner; the invention further consists in the means for readily and quickly determining the range to 35 which the gun is to be sighted, in the combination with said means of a sight rod adapted to be used independently, and in structural features and combinations of co-operative elements as will now be fully described, reference being had to the accompanying drawings, in which—

Figure 1 is a side elevation, Fig. 2 a top plan view, and Fig. 3 an end elevation of a 45 rear gun sight combined with means for determining the elevation of the gun in accordance with the range of fire. Fig. 4 is a longitudinal sectional view thereof. Fig. 5 is a transverse sectional view taken through the 50 pivot of the sight and range segments and

through the lock plate, showing means for illuminating the sight and range indicator. Fig. 6 is a diagram illustrative of the operation of the sighting devices. Fig. 7 is a sectional detail view of parts of Fig. 5 drawn to 55 an enlarged scale, and Fig. 8 is a diagram illustrative of the electrical connections of the incandescent lamps used for illuminating the sights.

Similar letters indicate like parts wherever 60 such may occur in the figures of drawings just described.

Referring to Figs. 1 to 4 inclusive, which illustrate the sighting device as constructed for day use only, B, indicates a base plate that 65 is secured to the gun barrel, said plate being provided with blocks or standards, b and b' in which are formed bearings for a pivot pin, a, that is preferably formed integral with the rear sight, A, the end of the pin a projecting 70 beyond the bearing, b', and is provided in said projecting end with a peripheral groove engaged by a locking latch, c, pivoted to bearing, b', for the purpose of locking the pin and parts connected therewith against endwise 75 motion and for the purpose of readily removing the said pin and parts from the bearings, b, b', when this becomes desirable or necessary from any cause. The rear sight A is 80 constructed in the form of a segment or sector of a circle, and is arranged eccentrically relatively to its pin a, as shown in Figs. 1 and 3, the eccentric segmental sight being provided with a peripheral sight groove, d, that is V-shaped in cross-section, and constitutes 85 the sight notch. The eccentric segmental sight is arranged parallel with the major axis of the gun with its pin a at right angles thereto, and the direction of the sight groove d relatively to the axis of the gun barrel corresponds with the lateral deviation of the projectile.

To the outer side of the eccentric segmental sight is secured a segmental (preferably semi-circular) range indicator C, the periphery of which is graduated to distances or angles of elevation constituting a range scale of suitable amplitude, as for instance from two hundred to two thousand four hundred meters.

To the range indicator C is secured a semi-circular lock-plate D that has a peripheral flange overhanging a portion of the periphery of the range indicator and is provided with 5 lock notches d' , corresponding with the range graduations on said indicator so that the angle through which the eccentric segmental sight A is to be revolved for the purpose of obtaining the desired sighting elevation, may 10 be readily determined.

To the lock plate D is secured a handle k, whereby the said lock-plate, the range indicator and eccentric segmental sight are simultaneously revolved. The parts are locked 15 into the positions to which they are or may be adjusted by means of a locking pawl or tooth e, secured to the free end of a leaf spring E, the opposite end of which is provided with a flange for securing the spring 20 to the base B, as shown in Figs. 2 and 3. To said spring E by the side of the locking tooth e, is also secured an inclined index plate f, the inclination of the plate being upwardly and forwardly, and said index plate is ar- 25 ranged to trail with its free edge on the graduated periphery of the range indicator and performs the function of an index hand or finger in setting the indicator to a given range.

30 When the apparatus is constructed for night service, as hereinafter described, the screws g, that secure the lock spring E to the base B, also serve to secure to said base an insulation block or plate h, of ebonite, for instance, that carries a metallic binding screw F, provided with a metallic arm i.

The pivot a for the sighting devices also carries between the bearings b, b', a sight rod G, adapted to be turned up or down, and is 40 held in the position to which it is adjusted by a leaf spring m secured to base plate B and having bearing on a radial lug or projection l, on the hub of said rod G as shown in Fig. 4. The rod is constructed in the form 45 of a rack bar having teeth g' formed along one of its edges, and on said rod is adjustably mounted a sight s³, provided with a sight notch sn. As shown in Fig. 2 the sight s³ projects from a slide n having bearings for a 50 revolvable spindle, s⁴, on which is secured a pinion p³, said spindle carrying a suitable milled head h³ whereby the sight is adjusted along the rod G. The lateral deviation of the sight notch sn from the vertical line 55 takes place in consequence of the laterally inclined position of the rod G when elevated, the required obliquity of the rod relatively to the major axis of the gun being obtained by boring the bearing for the pivot pin a at the 60 desired angle relatively to the major axis of the rod, so that when in use for sighting the sight line as determined by the adjustable sight n and the front sight of the gun will form an angle relatively to the major axis of said 65 gun corresponding with the deviation of the projectile, for well known purposes. This

sight rod is designed for use in slow firing, and for day service only.

As stated, the sighting devices may, with but very slight structural changes, be adapted to both day and night service, as shown in Figs. 5, 7, and 8, the pivot pin a, being of tubular form while the eccentric segmental sight and the semi-circular range indicator are constructed in the form of a casing, and 75 said parts may then be formed integral, as shown in Fig. 5. The eccentric segmental sight A, has closely arranged openings or perforations d⁸ along the line of greatest depth of the sight groove d, while the semi-circular 80 range indicator has a peripheral slot closed by a transparent or translucent plate r, of celluloid, for instance, on which the range indices are preferably marked in black, said plate being conveniently held in position in 85 a suitable peripheral recess by the overhanging flange d⁷ of the lock plate D, as shown in Fig. 5.

The illuminating device consists of an incandescent lamp L, whose neck is fitted in 90 an ivory tube O, contained in the pivot pin a, an elastic cushion, as a sleeve o, of vulcanized rubber being interposed between the said neck of the lamp and said ivory tube, so as to provide an elastic bearing for the lamp 95 and a safeguard against breakage. A portion of the neck of the lamp, L, near the bulb is inserted into a metallic socket or sleeve p, provided with an arm p', secured by means of a screw to the inner face of the eccentric 100 segmental sight A and range indicator C. The outer end of the neck of the lamp abuts against a metallic fixed plug q connected by a spring q² preferably of German silver, with a movable plug, q' in the outer end of the 105 ivory tube O, which plug, q' is in contact with the metallic arm i of the binding screw F, hereinbefore referred to. One of the leading in wires of the lamp, or one end of its 110 filament is connected with the metallic sleeve p', and consequently with the metallic eccentric segmental sight and range indicator, A, C, and its pin a, and through the latter and the bearing, b, b', with the metallic base, B, of the apparatus, hence with the gun, while 115 the other leading in wire or other end of the filament is connected with the plug q, and through the spring q² with plug, q', and binding screw F, through arm i hereinbefore referred to, so that the lamp can be readily 120 placed in an electric circuit.

In order that the necessary amount of light may reach the perforations d⁸ in sight groove d, I form them on lines oblique to the radius in the direction of the zone of incandescence 125 of the lamp filament.

When the lamp is in operation at night the celluloid range index plate r provided with the range indices in black will appear gray, so that said indices are readily discernible without injury to the eye, and in view 130 of the curvilinear arrangement of the light

perforations, d^3 , the observer will have in view a line of light of a dull green hue that is not dazzling to the eye, in fact, the intensity of the line of light is a gradually diminishing one in opposite directions from a point of greatest luminosity or intensity, as will be readily understood. Of course in order to obtain a greenish light which is least injurious or fatiguing to the eyes a green glass bulb is used on the incandescent lamp.

In conjunction with the described rear sight a front sight of any desired construction so as to be visible at night may be used.

In practice the illuminating devices for both front and rear sights are preferably included in the same battery circuit, as shown diagrammatically in Fig. 8, v indicating the incandescent lamp of the front sight, and L that of the rear sight, W and W' the line wires, K the circuit closer, and H the battery, a current strength of from four to five volts having been found ample for both lamps.

It is of course desirable that the conductors that connect the lamps with the source of electricity should not only be thoroughly insulated, but that they should also possess the necessary flexibility, for obvious reasons, while the battery H or other electrical source should be so located as to be protected against shock.

In Fig. 6 I have illustrated the operation of the sighting apparatus diagrammatically, a , being the axis of rotation of the sight, A , which is shown in its lowermost or depressed position in full lines, and in its uppermost or highest and in an intermediate position by dotted lines, indicated by A^2 , A' , respectively, d , d^2 , d' , indicating the sight point when the sight is in the positions of A , A^2 , A' , respectively, a^5 , a^4 , the angles of rotation for the corresponding heights of the sight points, d^2 , d' , and S is the front sight.

I have referred to ivory tubes in respect of the connections for the lamp L , as an insulating material, but do not wish to confine myself thereto, as other suitable insulating materials may be used in the construction of these tubes.

Having thus described my invention, what I claim as new therein, and desire to secure by Letters Patent, is—

1. A rear sight for guns, comprising a revolute eccentric segmental sight, a segmental range indicator having a fixed relation relatively to but revolute with the sight, and a locking device for locking said parts into position, for the purpose set forth.

2. A rear sight for guns, comprising a revolute eccentric segmental sight, provided with a peripheral sight groove, V-shaped in cross section, a segmental range indicator formed integral with the sight, a ratchet segment connected with the range indicator, and a spring pawl engaging the teeth of the ratchet, for the purpose set forth.

3. A rear sight for guns comprising a revolute eccentric segmental sight, a segmental

range indicator having a fixed relation relatively to but revolute with the sight, a fixed index finger plate in contact with the range indicator, and a locking device for locking said parts into position, for the purpose set forth.

4. A rear sight for guns comprising a revolute eccentric segmental sight, provided with a peripheral sight groove, V-shaped in cross section, a segmental range indicator formed integral with the sight, a ratchet segment connected with the range indicator, a spring pawl engaging the teeth of the ratchet, and an index finger connected with the spring of the pawl and adapted to trail over the range indices, for the purpose set forth.

5. A rear sight for guns, comprising a base adapted to be secured to the gun, a revolute eccentric segmental sight provided with a peripheral sight groove V-shaped in cross section, a segmental range indicator revolute with and having a fixed relation relatively to said sight, a segmental ratchet secured to the range indicator provided with ratchet teeth the interspaces of which coincide with the graduations on said indicator, a spring pawl in engagement with said teeth, and a pivot pin rigidly secured to the sight, said pin revolute in bearings on the base, for the purpose set forth.

6. A rear sight for guns, comprising a base adapted to be secured to the gun, a revolute eccentric segmental sight provided with a peripheral sight groove V-shaped in cross section, a segmental range indicator revolute with and having a fixed relation relatively to said sight, a segmental ratchet secured to the range indicator, provided with ratchet teeth the interspaces of which coincide with the graduations on said indicator, a spring pawl in engagement with said teeth, and a pivot pin rigidly secured to the sight, said pin revolute in bearings on the base and provided at its outer end with a peripheral groove, in combination with a locking latch adapted to engage said groove, for the purpose set forth.

7. A rear sight for guns, comprising a revolute eccentric segmental sight, a segmental range indicator revolute with and having a fixed relation relatively to said sight, and a locking device for locking the parts into position, in combination with a graduated sight rod revolute independently of the sight and range indicator, and a sight adjustable along said rod, for the purpose set forth.

8. A rear sight for guns, comprising a revolute eccentric segmental sight, a segmental range indicator revolute with and having a fixed relation relatively to said sight and a locking device for locking the parts into position, in combination with a graduated sight rod revolute independently of the sight and range indicator, a sight adjustable along said rod, and a pivot common to said devices, for the purpose set forth.

9. A rear sight for guns, comprising a revolute eccentric segmental sight, a segmental range indicator revolute with and having a

fixed relation relatively to said sight, and a locking device for locking the parts into position, in combination with a graduated sight rod revoluble independently of the sight and 5 range indicator, said rod constructed in the form of a rack bar, a slide, a pinion in gear with the teeth of the rod mounted on said slide, and a sight secured to the slide, for the purpose set forth.

10. A rear sight for guns comprising a revoluble segmental chambered sight, provided with a light transmitting peripheral sighting line in combination with an illuminating device contained within the sight, for the purposes set forth.

11. A rear sight for guns comprising a revoluble segmental chambered sight provided with a peripheral light transmitting sighting line and a segmental chambered range finder 20 revoluble with the sight and provided with a light transmitting peripheral scale, in combination with means for illuminating the interior of said devices.

12. A rear sight for guns, comprising a hollow revoluble eccentric segmental sight provided with a peripheral groove V-shaped in cross section, and with perforations along the apex of said groove, and an illuminating device contained within the sight, for the purposes set forth.

13. A rear sight for guns comprising a hollow revoluble eccentric segmental sight provided with a peripheral groove V-shaped in cross section and with perforations along the

apex of said groove, a segmental hollow range 35 indicator connected with the sight and provided with a transparent or translucent scale plate and an illuminating device arranged within the sight and range indicator, for the purpose set forth.

14. In a rear sight for guns the combination of the following instrumentalities; a metallic eccentric segmental casing, A, C, constructed relatively to each other as described, the portion A, provided with a peripheral groove V-shaped in cross section and with perforations along the apex of the groove, said perforations formed on lines oblique to the radius, the portion C provided with a transparent or translucent plate r, having range indices 50 thereon, a tubular pivot for said casing, suitable bearings for the pivot, an incandescent lamp seated in and insulated from said pivot, a metallic bearing for the lamp secured to the casing C, and electrically connected with one 55 end of the lamp filament, and with one pole of a source of electricity, and a conductor extending through and insulated from the hollow pivot connecting the other end of said filament with the opposite pole of the source 60 of electricity, as set forth.

In testimony whereof I affix my signature in presence of two witnesses.
